UNITED STATES PATENT OFFICE.

LAURA S. COONEY, OF NEW YORK, N. Y.

DESIGN FOR A SUSPENDER-WAIST.

47,710.

Specification for Design.

Patented Aug. 17, 1915.

Application filed April 9, 1915. Serial No. 20,338. Term of patent 7 years.

To all whom it may concern:

Be it known that I, LAURA S. COONEY, a citizen of the United States, and a resident of the city of New York, borough of Brooklyn, in the county of Kings and State of New York, have invented a new and original Design for Suspender-Waists, of which the following is a specification.

Reference is to be had to the accompanying drawing in which the figure is a perspective view of a waist illustrating my new design.

I claim:—

The design for a suspender waist, as shown.

LAURA S. COONEY.
